(57) **CLAIM**

The ornamental design for a vehicle seat base, substantially as shown and described.

DESCRIPTION

FIGS. 1 and 2 are perspective views of a vehicle seat base.

FIG. 3 is a front view of the vehicle seat base.

FIG. 4 is a left side view of the vehicle seat base.

FIG. 5 is a rear view of the vehicle seat base.

FIG. 6 is a right side view of the vehicle seat base.

FIG. 7 is a top view of the vehicle seat base; and,

FIG. 8 is a bottom view of the vehicle seat base.

The dotted line portions of the drawing represent environmental structure only and do not form part of the claimed design.
